ANIMATED FIGURE TOY

Obi Erickson, Eagle Grove, Iowa, assignor of one-fourth to Russell W. Good and one-fourth to Carl N. Sunner, both of Eagle Grove, Iowa

Application July 31, 1934, Serial No. 737,822

3 Claims. (Cl. 46—40)

This invention relates to figure toys of the mechanical animated variety and has more particular reference to a structure embodying a bird fashioned to represent a woodpecker and constructed for operation in conjunction with a simple wind motor.

In introducing this invention as a novel contribution to the trade and the art I am not unmindful of the fact that the field of invention to which it pertains discloses a multitude of different figure toys of various types including loose jointed parts activated by mechanical means. In fact I am conversant with prior patented wind operated toys wherein a simple motor embodying a rotary shaft and operating fan is correlated with the limbs and other portions of the toy to produce the desired life-like actions.

By way of contrast the invention constituting the subject matter herein disclosed has to do with a simple and economical stand constituting a support for a wind rotated power supply stand and a support for a unique toy designed to provide the desired intriguing and amusing results for juveniles.

The particular construction adopted as representative of the preferred embodiment of the invention will become more readily apparent from the accompanying illustrative drawings and the complementary explanatory descriptive matter.

In the drawings:

Figure 1 is a side elevational view of the assembly constituting the preferred embodiment of the invention.

Figure 2 is a vertical sectional view taken approximately on the plane of the line 2—2 of Figure 1 looking in the direction of the arrows.

Figure 3 is a similar sectional view looking in an opposite direction and taken on the plane of the vertical line 3—3 of Figure 1.

Figure 4 is an end elevational view of the figure constituting a representation of the so-called woodpecker.

Referring to the general assembly illustrated in Figure 1 it will be observed that the support comprises a suitable base 5 and a standard 6 forming a pedestal for supporting the horizontally disposed top bar 7. The top bar is, broadly stated, a head and serves as a convenient adapter for the wind motor and toy figure. The wind motor comprises a rotary bladed fan or propellor 8 secured operatively to one end of a horizontal power transmitting shaft 9. The shaft is suitably journaled in a bearing at the left hand end and at its opposite end is provided with an ac-

tuating crank 10 confined within the limits of the mechanism or chamber or compartment 11 of the figure toy. As before stated the toy is fashioned to represent a woodpecker. It comprises a casing 12 of appropriate shape and dimension which is secured to one end of the head 7 and which is provided at its lower end with an imitation tail 13 above which is a slot 14 permitting access to be had to the compartment 11. In the top or crown portion of the shell like casing is a slot 15 to accommodate the oscillatory head unit 16. This head unit is in the form of a pendulous member and includes a head 17 and a shank portion 18 the shank being pivotally mounted in the shell as indicated at 19. The head is shaped to represent that of a woodpecker and is appropriately formed in relationship to the remainder of the body and tail structure to provide the desired representative features. It is therefore formed with a suitable 20 bill or beak 20. In action it is supposed to move up and down in a step by step or progressive manner to provide the desired life like pecking motions for the head and bill. Generally stated it has three distinct positions, that is the perpendicular full line position shown in Figure 3, the lower dotted line position indicated at 21 and the intermediate position indicated by dotted lines as at 22. This movement is accomplished by the action of the crank 10 and the complementary features. It will be noticed that the edge portion 23 (see Figure 3) is curved to provide a cam. The lower end portion of the shank is cut off on a diagonal line and fastened to this at one end as indicated at 24 is a heavy 35 rubber strip 25 which functions as a trip element. The free end portion 26 projects beyond the cam edge 23 in a position to be in the path of movement of the revoluble crank 10. The numeral 27 designates a keeper notch in which one 40 end of a rubber band or equivalent element 28 is located, this band partially embracing the shank and being anchored on a pin as indicated at 29. All of these essential parts are concealed and confined within the compartment 11 of the shell. 45 It is noted, of course, that the trip forming element 25 is fastened at one end while the opposite end 26 is free to flex away from the diagonal or biased lower edge of the shank 18. The angle to which the element 25 flexes with respect to the lower edge of the shank is shown in dotted lines in Figure 3 of the drawings. The crank 10 turns counter clockwise and the parts are positioned as shown in Figure 3 of the drawings at the beginning of the downward stroke. 55

As the crank bears on cam 23 the head 17 is moved uniformly downwardly to the end of the stroke and against the tension of the rubber band 28 and the end of the stroke is indicated 5 by dotted line position 21. At this point, crank 10 slips off cam 23 but bears solely on trip 26 in which case the rubber band acting on shank 18 snaps body 16 back to the dotted line position indicated at 22 while element 25 flexes away 10 from the lower edge of the shank 18, and at the dotted line position 22 there is a slight oscillatory movement followed by a momentary pause. As crank 10 continues its rotation bearing solely on member 25 it slips off extension 15 26 and is returned by rubber band 28 to upright position shown in full lines in Figure 3 of the drawings ready for another cycle of operation. The foregoing described movements result in the simulation of the pecking action of a 20 woodpecker.

Novelty is predicated upon a portable pedestal serving as a support for the wind motor and the figure toy. The principal novelty, however, is based upon the construction of the toy itself, especially the details illustrated in Figure 3.

It is thought that persons skilled in the art to which the invention relates will be able to obtain a clear understanding of the invention after considering the description in connection with 30 the drawings. Therefore, a more lengthy description is regarded as unnecessary.

Minor changes in shape, size, and rearrangement of details coming within the field of invention claimed may be resorted to in actual 35 practice, if desired.

Having thus described my invention, what I claim as new is:

1. As a new article of manufacture a toy figure constructed in outline and shape to represent 40 a woodpecker and including a hollow shell defining a mechanism compartment, said shell provided at its lower end with a depending tail and at its upper end with a guide slot, a head unit having a portion extending into said shell through 45 said slot and pivoted in said shell, said extended end portion being provided with a keeper notch, a rubber band extending through said notch and anchored at one end in said shell to move the head in one direction in the slot, said extended 50 end portion being further provided on its lower

end with a flexible trip element, and a power operated shaft including a crank mounted for rotation in said shell and cooperable with the adjacent edge portion of said extension as well as the adjacent end portion of said trip. 5

2. The combination with a rotatable support carrying a wind motor and a drive shaft connected with the motor of a slotted body shell constructed to simulate a woodpecker, said drive shaft journaled to said body shell and formed 10 with a crank, rotatable within the body shell, a head simulating member pivoted to said body shell having a pendant portion extending through the slot into the body shell in a certain arc in the revolution of the crank for the purpose of 15 rocking the head member from the uppermost to the lowermost limit of the pecking stroke, retractile means coacting with the head member to return the head member to the uppermost limit from the lowermost limit of the pecking 20 stroke, and flexible means carried by the pendant portion of the head member lying in another arc of revolution of the crank independent of the first mentioned arc whereby the return of the head member from the lowermost to the uppermost limit is arrested at an intermediate point in the return pecking stroke giving an oscillatory movement followed by a pause. 25

3. A figure toy comprising a slotted body shell constructed to simulate a woodpecker, a power 30 driven crank journaled to the shell body for rotation therein, a head simulating member pivoted to said body having a pendant portion extending through the slot in a certain arc in the revolution of the crank for the purpose of rock- 35 ing the head member from the uppermost to the lowermost limit of the pecking stroke, retractile means coacting with the head member to return the head member to the uppermost limit from the lowermost limit of the pecking stroke, 40 and flexible means carried by the pendant portion of the head member lying in another arc of the revolution of crank independent of the first mentioned arc whereby the return of the head 45 member from the lowermost to the uppermost limit is arrested at an intermediate point in the return stroke giving an oscillatory movement followed by a pause.

OBI ERICKSON. 50.
